UNITED STATES PATENT OFFICE.

GEORGE R. MOSS AND ROBERT D. PARKS, OF LOHRVILLE, IOWA, ASSIGNEES TO J. J. McCULLOCH, OF POMEROY, IOWA, AND SILAS C. SWEET, OF DES MOINES, IOWA.

BARN AND GARAGE DOOR LATCH.

Application filed October 30, 1926. Serial No. 145,195.

An object of this invention is to provide an improved construction for a latch, particularly adapted for use on barn and garage doors.

A further object of this invention is to provide an improved construction for a strike for latches.

A further object of this invention is to provide an improved latch adapted to be mounted on and operated with a swinging or sliding door.

A further object of this invention is to provide an improved means of mounting a lifting device for a latch.

Our invention consists in the construction, arrangement and combination of elements hereinafter set forth, pointed out in the claims and illustrated by the accompanying drawing, in which—

Figure 1 is an outside elevation illustrating the construction and mounting of the complete device as for practical use. Figure 2 is a side elevation of the same, partly in section on the indicated line 2—2 of Figure 1. Figure 3 is a partial horizontal section on the indicated line 3—3 of Figure 1, the latch member and lifting device particularly being shown in full lines. Figure 4 is a vertical section on the indicated line 4—4 of Figure 1. Figure 5 is an elevation at the inner face of the door, partly in section on the indicated line 5—5 of Figure 4. Figure 6 is a front elevation showing the base plate and latch member detached from the door, the latch member being turned through an arc relative to the base plate to reveal otherwise hidden construction. Figure 7 is an end elevation of an angle plate adapted to be mounted on a door. Figure 8 is an end elevation of a strike adapted to be mounted on a wall or jamb adjacent a door. Figures 9 and 10 are elevations, at right angles to each other, of a hold-back strike adapted to be mounted on a support such as a wall and spaced from a doorway. Figure 11 is a plan of the device shown in Figures 9 and 10.

This specification and the drawing referred to therein contain some of the elements illustrated, and described in the companion application of John J. McCulloch, and the inventions of both applications are owned by said McCulloch and Silas C. Sweet jointly, hence no interference is desired between the claims thereof.

In the construction of the device as shown the numeral 10 designates a base plate, which

is formed with a recurved hook 11 on one end and holes 12 adapted to receive screws whereby it may be secured to a door 13. A latch member 14 is adapted to be pivoted at one end on one end portion of the base plate 10, preferably by a screw 15 extending freely through registering holes in the plate and latch member. The free end portion of the latch member 14 is adapted to be received within the hook 11 and is formed with notches 16, 17 in opposite margins and a truncated arrow-shaped extremity outside said notches. The base plate 10 also is formed with a rectangular opening 18 between the holes 12 and screw 15 and the length of said opening preferably is transversely of the plate. The latch member 14 also is formed with a slot 19 arranged longitudinally thereof and adapted to overlie a portion of the opening 18 and overlap at one end on the plate 10 at one side of said opening, the length of said slot being greater than the width of said opening. A hole 20 is formed in the door 13 and registers with the opening 18 in the base plate. A door-pull or handle 21 is mounted on the inner face of the door 13, after the other parts are assembled and the uppermost ear 22 thereof extends across the inner end of the hole 20 and is formed with a slot 23 arranged transversely of said hole and registering therewith. A lift 24 is formed of a bar of metal bent substantially at right angles near its center to produce a handle portion 25 on one end. The lift 24 is adapted to extend through and fit loosely in the slots 19 and 23 and extend through the hole 20. The lift is of greater width than the opening 18 and is formed with a notch 26 in one margin adapted to receive and pivot the lift on the plate 10 at one side or wall of the opening. In assembling the parts, the lift is turned with its handle portion 25 in horizontal position and passed through the opening 18 and hole 20 before the door-pull 21 is placed in position, and then is turned into vertical position as shown so that the notch 26 will receive the adjacent wall of said opening. This is done after the plate 10 is mounted on the door and before the latch member 14 is brought into contact with the plate. The latch member is mounted on the lift member and the latter may be oscillated in the opening 18 enough to permit said latch member to be placed against the plate, with one end thereof within the hook 11, before the screw 15 is placed to connect them. The handle por-

105
106
110

tion 25 depends outside of the door 13 and is spaced therefrom for convenience in grasping and the lower end portion thereof is bent inwardly and normally contacts with the door. A clip 27 is mounted on the outer face of the door 13 and loosely confines the lower end portion of the handle 25, permitting oscillation thereof relative to the door. The base plate 10 is so mounted that its hooked end portion extends across the adjacent edge of the door, and an angle plate 28 is mounted on the outer face of the door and is formed with an outstanding ear 29 substantially flush with the edge, which ear is formed with notches 30 and 31 in its upper and lower margins and a hole 32 in its body adapted to receive a padlock, not shown. A strike 33 is mounted in or on and substantially flush with the jamb 34 of the doorway and projects outwardly therefrom. The strike 33 is formed with notches 35, 36 in its upper and lower margins adapted to register at times with the notches 30 and 31 of the angle plate 28 and the uppermost of said notches (dependent on the arrangement of the latch for right or left opening of the door) are adapted to receive the latch member 14 and engage and retain the same. The notch 17 or the notch 16 (dependent on the arrangement as to right or left opening of the door) embraces the ear 29 and strike 33 and limits longitudinal movement of the door when it is slidably mounted. The strike 33 is formed with inclined marginal portions 37, 38 adapted to engage and lift the base plate 10, and latch member 14 at times, when the door is mounted for swinging relative to the jamb. The strike 33 also is formed with a hole 39 in its body adapted to register with the hole 32 in the angle plate 28 and receive a padlock, not shown. A guard 40 is formed integral with the outer end of the strike 33 and extends obliquely therefrom and is adapted to be secured by a screw 41 to a wall 42 of which the jamb 34 forms a part. The guard prevents catching of harness, curtains, clothing and the like on the strike 33 and also serves as a brace for said strike. The lift member extends both in front and at the rear of the door 13 and is adapted to be manipulated, by outward pull on the handle portion 25 of thumb pressure on its inner end, to oscillate it and cause it to lift the latch member 14 out of engagement with the strike 33. In any oscillation the lift member fulcrums on the lower margin of the slot 23 in the ear 22 and has sufficient movement to raise the latch member by engagement with the upper margin of the slot 19. Ordinarily the latch member seats by gravity after any manipulation thereof in use. In the event of an accumulation of frost, snow or ice tending to stick the latch member in open position, it can be released by opposite operation of the handle member 25 or of the inner end portion of the lift member. When the device is in

latched position, the door being either swinging or sliding relative to the wall, the outer end portion of the base plate rides on a shoulder 43 of the strike 33 and supports the door against sagging. A hold-back strike is formed of an angular bar of metal (Figs. 9, 10, 11) having a base flange 44 provided with notches 45, 46 opening through its lower margin and adapted to receive screws whereby it may be fastened to a wall back of the door way, when the door is hinged for swinging, in substantially the same horizontal plane as the strike 33. The outstanding flange 47 is formed with a notch 48 in its upper margin adapted to receive the latch member 14 when the door is open, a shoulder 49 receiving and supporting the latch plate 10 when the door is open and preventing sagging thereof and an inclined margin 46 outside said shoulder adapted to receive and guide the base plate to its seat and raise the door slightly if it is sagged. The latch member 14 and base plate 10 may be inverted longitudinally for use on a door opening oppositely to that shown, in which event the strike 33 would be mounted on the opposite jamb (not shown). The depending handle portion 25 of the lift 24 may serve as a door-pull, the pulling strain applied thereto being communicated to the door through the clip 27 and through engagement of the lift by its notch 26 with the base plate 10.

We claim as our invention—

1. A barn and garage door latch, comprising a base plate formed with an opening and a curved, overlapping end portion, a latch plate pivoted on said base plate and formed with a slot extending across said opening at times, one end of said latch being received under said overlapping end portion, a lift member extending through said opening and slot and arranged for oscillation therein, and a handle integral with said lift member and depending from one end portion thereof. 100

2. A barn and garage door latch, comprising a base plate formed with an opening and a curved, overlapping end portion, a latch member pivoted on said base plate and formed with a slot extending across said opening at times, one end of said latch being received under said overlapping end portion, a lift member extending through said opening and slot and arranged for oscillation therein, a handle integral with said lift and depending from one end portion thereof, and a clip adapted to embrace and limit arcuate movement of said handle. 115

3. A barn and garage door latch, comprising a base plate formed with an opening and a curved, overlapping end portion, a latch member pivoted on said base plate and formed with a slot extending across said opening at times, one end of said latch being received under said overlapping end portion, a lift, 125 formed with a marginal notch, extending 130

through said opening and slot, said notch engaging the base plate at one side of said opening, and a strike adapted to be engaged by said latch member.

5. 4. A barn and garage door latch, comprising a base plate formed with an opening, a latch member pivoted on said base plate and formed with a slot extending across said opening at times, a lift member formed with

a marginal notch adapted to engage said base plate, a door-pull formed with a slot adapted to receive and fulcrum said lift member, a handle on said lift member, and a strike adapted to engage said latch member.

Signed at Lohrville, Iowa, this 2nd day of 15
January, 1925.

GEORGE R. MOSS.
